FRED D. PERRY, OF EAST BAKERSFIELD, CALIFORNIA

LID FASTENING DEVICE FOR SHIPPING CASES

Application filed September 9, 1929. Serial No. 391,338.

My invention relates to crates, boxes, and similar forms of shipping cases, and it has particular reference to devices for fastening the removable lids of shipping cases in closed position thereon.

It is a purpose of my invention to provide a lid fastening device for shipping cases which is characterized by its simplicity of construction, durability, easy mode of application, and the facility and dispatch with which the case lid may be secured in fixed position on the case, and also removed therefrom, without in any manner destroying the usefulness of the lid.

I will describe only one form of shipping case and one form of lid fastening device embodying my invention, and will then point out the novel features thereof in claims.

In the accompanying drawings:

Fig. 1 is a view showing in end elevation a shipping case having applied thereto one form of lid fastening device embodying my invention.

Fig. 2 is a fragmentary vertical sectional view taken on the line 2—2 of Fig. 1.

Fig. 3 is a fragmentary plan view of a shipping case showing the fastening device in applied position.

Fig. 4 is an enlarged fragmentary view showing in front elevation the actuating lever and the mounting therefor, both in applied position to the shipping case.

Fig. 5 is a vertical sectional view taken on the line 5—5 of Fig. 4.

Figs. 6 and 7 are detailed perspective views of the lever and mounting shown in Figs. 4 and 5.

Referring specifically to the drawings, my invention in its present embodiment comprises one or two lid fastening devices depending upon the nature of the shipping case lid with which it is adapted to be associated.

For example, where the lid of the shipping case is permanently attached at one end to the body of a shipping case, only one such fastening device is employed, but where the lid is not permanently connected to the shipping case but is adapted to be completely removed therefrom, two such fastening devices are employed and associated with the shipping case

to engage the ends of the lid in a manner to securely retain the latter in fixed position upon the case. Hence, it will be understood that although I have illustrated herein, and will describe only one of the devices and the manner in which it is associated with a shipping case and its lid, I do not wish to be restricted to the use of a single device. 55

In Figs. 1, 2 and 3, I have shown one end of a shipping case, and a portion of a lid therefor. The end wall of the shipping case is indicated at 15, and to the outer side of this wall adjacent the upper edge thereof is secured a strip 16 preferably formed of wood and co-extensive in width with that of the shipping case. Adjacent the ends of the strip 16 diagonal recesses 17 are formed in the outer face thereof with one wall of each recess cupped as indicated at 17^a and for a purpose to be described hereinafter. As best illustrated in Fig. 2, the lid of the shipping case indicated at 18 is of such length that its end projects beyond the end wall 15 so as to overlie the strip 16 and extend across the upper ends of the recesses 17. 70

The device proper comprises a clamping member indicated generally at C and which in the present instance is constructed from a single length of resilient wire bent in the form of a triangle to provide an intermediate portion 19 and converging end portions 20, the intermediate portion being connected to the end portions by linear portions 21 disposed substantially at right angles to the portion 19 and at obtuse angles with respect to the end portions 20. The free ends of the portions 20 terminate in hooks 22 adapted to engage within ears 23 of a lever 24, the latter having its upper end curled upon itself to form a sleeve 25 through which extends a pintle 26. This pintle 26 is mounted in ears 27 formed on a plate 28 secured to the outer side of the wall 15 by screws 29 or in any other suitable manner. The lever 24 constitutes an actuator for the clamping member C, and the pintle 26 constitutes an axis for the lever about which the latter is adapted to swing in effecting actuation of the clamping member. The plate 28 together with its ears 27 provides a mounting for the 100

lever, and it is shown as formed with a stud 30 adapted to be received in an opening 31 of the lever 24 and provided with an opening 30^a through which a sealing device 32 5 may be extended.

In the applied position of the fastening device with respect to the shipping case, the mounting plate 28 is secured to the outer side of the wall 15 as has been described, while the 10 clamping member is arranged so that its end portions 20 are extended through the recesses 17, with the intermediate portion 19 disposed to the upper side of the strip 16 and extending transversely of the end of the shipping 15 case.

In the inactive or released position of the device as shown in the dash lines in Fig. 2, the clamping member is elevated so that the intermediate portion 19 is sufficiently spaced 20 from the top of the case as to permit the ready insertion of the lid end 18 therebeneath. In this position of the clamping member the lever 24 likewise occupies an elevated position in which it is sufficiently spaced from the 25 wall 15 that it may be readily gripped and moved to lowered position for drawing the clamping member downwardly so that the intermediate portion 19 is caused to tightly embrace the lid end and thus securely retain 30 the lid in fixed position upon the shipping case. The lowermost position of the lever 24 is illustrated in Figs. 4 and 5, and in this position of the lever it is important to note that the pivotal connection between the 35 clamping member and the lever as provided by the hooked ends 22 and the ears 23, is positioned at one side of the pivot 26 of the lever. The intermediate portion 19 of the clamping member is bowed downwardly or 40 in the direction of the lid, and being formed of resilient metal, it is apparent that when the clamping member is forced downwardly through actuation of the lever 24, the intermediate portion 19 will be flexed and thus placed under tension. By reason of this tension the intermediate portion constantly acts 45 to urge the clamping member upwardly, but this urging action is ineffective to swing the lever upwardly by reason of the position of 50 the pivotal connection between the clamping member and lever. In other words, this pivotal connection is in a past dead center position with respect to the pivot 26, and consequently any pull exerted upwardly by the 55 clamping member will tend to retain the lever in the position illustrated in Fig. 5. In consequence of this mode of operation, it will be manifest that once the lever is moved to 60 actuate the clamping member, the latter is retained in clamping position with respect to the lid with such a degree of security as to prevent the accidental release of the clamping member. Yet, this action does not interfere with the ready release of the fastening device for it is only necessary to move 65

the lever outwardly past dead center position when the intermediate portion 19 will react to throw the lever to elevated position and thus permit such elevation of the clamping member that the lid is disengaged and may thus be removed.

In the active position of the lever 24 the stud 30 projects through the lever as illustrated in Fig. 5 so that the sealing device 32 may be extended through the opening 30^a. Once the sealing device is applied, the lever cannot be actuated to release the lid without detection.

An important feature of my invention is the coaction between the linear portions 21 and the dished walls 17^a of the recesses. As the clamping member is drawn downwardly by actuation of the lever 24, the linear portions 21 move into the dished walls 17^a and remain therein even in the final clamping position of the member. The dishing of these walls is such that they provide abutments for the linear portions 21 to prevent movement of the latter horizontally and as a consequence the lid 18 is firmly held against any edgewise or transverse shifting. Thus, with the clamping member in clamping position, the lid is securely held in closed position on the case.

Although I have herein shown and described only one form of shipping case and one form of lid fastening device embodying my invention, it is to be understood that various changes and modifications may be made herein without departing from the spirit of the invention and the spirit and scope of the appended claims.

I claim:

1. In combination, a shipping case having a removable lid, recessed elements at opposite sides of the shipping case so disposed as to have portions of the lid bridging said recesses, clamping members extending through said recesses and having portions disposed at the outer side of the lid and spanning the latter, and means on the shipping case for actuating the clamping members to cause said portions to clamp the lid in closed position on the shipping case.

2. In combination, a shipping case having a removable lid, recessed elements at opposite sides of the shipping case so disposed as to have portions of the lid bridging said recesses, resilient clamping members extending through said recesses and having portions disposed at the outer side of the lid and spanning the latter, levers for actuating the clamping members to cause said portions to clamp the lid in closed position on the shipping case, and an operative connection between the members and the levers in which the levers may assume a past dead center position when said portions are in clamping position with respect to the lid so as to retain said portions in said position.

3. In combination, a shipping case having a removable lid, strips secured to the opposite ends of the case and provided with recesses, a pair of clamping members, each constructed of resilient wire and of substantially triangular formation to provide an intermediate portion spanning one end of the lid and overlying the latter, and end portions extending downwardly through the recesses, a pair of levers each connected to the end portions of the corresponding clamping member, and means for mounting the levers on the case so that upon actuation thereof, the clamping members will be drawn downwardly and held in a position in which the intermediate portions embrace the ends of the lid to hold the latter in closed position on the shipping case.
